(57) **CLAIM**

The ornamental design for a medical retractor as shown and described herein.

DESCRIPTION

FIG. 1 is a top, front, right side perspective view of a medical retractor according to the present invention; FIG. 2 is a front elevation view of the medical retractor shown in FIG. 1.

FIG. 3 is a rear elevation view of the medical retractor shown in FIG. 1.

FIG. 4 is a left side elevation view of the medical retractor shown in FIG. 1.

FIG. 5 is a right side elevation view of the medical retractor shown in FIG. 1.

FIG. 6 is a top plan view of the medical retractor shown in FIG. 1.

FIG. 7 is a bottom plan view of the medical retractor shown in FIG. 1; and,

FIG. 8 is a top, front, right side perspective view of the medical retractor shown in FIG. 1 in an alternative position. The broken lines in the drawings show portions of the medical retractor that form no part of the claimed design.

1 Claim, 6 Drawing Sheets
